5 Claims. (Cl. 88—24)

Application has been filed in Germany, December 20, 1939.

The invention relates to a reproduction apparatus for making color separations according to a colored specimen and where register marks are recorded on a photo-sensitive layer simultaneously with the reproduction specimen. Up to the present a planoparallel glass plate disposed in an object-plane was usually employed, the glass plate having had a margin impervious to light and provided with a plurality of register marks erased in the shape of cross lines. This arrangement of register marks either requires a corresponding number of glass plates for the different sizes of picture sections and picture sizes or, when using only one single glass plate with fixed register marks for the entire image field, it makes it necessary that the color separations be made of the full picture size in first place whereupon these are masked down to the required size, so that this procedure involves the waste of a considerable amount of material.

To do away with these drawbacks a virtual image of each one of the register marks adaptable in its position to the field of the reproduction specimen, is according to the invention being projected in the object-plane so that each of the register marks is sharply reproduced simultaneously with the reproduction specimen on the same photo-sensitive layer. It is possible, for instance, to produce the virtual image of a register mark by means of a mirror, or of a lens, or by a combination of lens and mirror system.

This method of depicting the register marks not only eliminates the aforementioned drawbacks, but also affords the possibility of obtaining on the photo-sensitive layer a good depiction of the register marks without diffusion of light in the layer, independent of the exposure-periods for the different color separations, provided that each of the register marks is being illuminated by a light-source whose brightness is regulatable. The arrangement can also be such that all register marks are being illuminated by one single light-source via a system of mirrors.

To easily adapt the register marks to the picture size it will be of advantage to have each of them adjustably disposed, preferably on a cross slide.

Where only a section instead of the whole field of a color photograph is required for the colored print it will be of advantage if to each of the register marks part of a mask is coordinated forming part of the margin representing the picture gate. In order to make it conveniently pos-

sible also to coordinate the register marks to a section of the picture lying in the corner of the field it will be furthermore of advantage to adjustably dispose each of the register marks, preferably on a cross slide, independent of the respective part of the mask.

A constructional example of the invention is illustrated in Figs. 1 to 5 of the annexed drawings, viz.:

10 Fig. 1 showing the reproduction apparatus in plan view and partly in longitudinal section.

Fig. 2 holding device for color-photograph in plan view and partly in section.

Fig. 3 holding device, top view,

15 Fig. 4 holding device for holding the glass plates.

Fig. 5 a further example for producing a virtual image of a register mark.

In Fig. 1 a reproduction apparatus is illus- 20 trated containing a light-source 1 which is being imaged at the place of a collective lens 3 by means of a two-component condenser lens 2.

Said collective lens 3 images the aperture of the 25 condenser lens at the place of an object 4. The object may be a color-photograph taken on a film or on a glass plate. The number 5 designates register marks disposed outside the object-plane near the margin of the photograph. By means of a mirror 6 each one of the register marks is 30 being presented to the objective 7 of the reproduction apparatus as lying in the object-plane and is being sharply reproduced on a photo-sensitive layer 8 together with film to be reproduced. A color filter 9 intended for the corresponding 35 color separation is disposed insertably in the path of rays between the collective lens 3 and the object 4. A concave mirror 10 is provided for on the rear of the camera housing 11.

Figs. 2 to 4 show the holding device for the ob- 40 ject 4, the device consisting of a plate 12 which is to be imagined to be disposed in the camera housing 11 in the object-plane and which is pro- 45 vided with an opening 13 for a 24 x 36 mm. color photograph. This opening is covered with a planoparallel glass plate 14 inserted in the plate 12. A second planoparallel glass plate 15 is co- 50 ordinated to plate 14 which, as shown in Fig. 4, is held to plate 12 by means of four double-armed gripping bodies 16. Each of the latter bodies is seated on a screw 17 which is disposed at the plate and which can either be tightened or loosened by means of an adjusting head 18. Between the plate 12 and the gripping body 16 a helical spring 19 is disposed on a screw for releasing the 55 grip the gripping body has on the glass plate 15.

In Fig. 3, only the screw heads 18 are shown of said holding device, while for reason of better clearness the holding device is not drawn in Fig. 2. Between the two glass plates 14 and 15 a color-film 20 as well as the four mask-parts 21, 22, 23 and 24 are located. To each one of said mask-parts a register mark 5 in the form of cross lines is coordinated, the register mark being disposed on the lateral surface of a glass prism 25 and being presented to the objective 7 of the reproduction apparatus through the reflecting surface 26 as lying in the plane of the color-film. Each prism 25 is seated in a supporting body 27 wherein it can be adjusted parallel to the optic axis of the apparatus. On a cross slide 28 and by means of a sliding foot 29 each supporting body 27 is displaceably disposed in a slide-rail 30 running parallel to the outer edge of the mask-part bounding the picture and can be fixed in position by means of a clamping screw 31. Each cross slide 28 is mounted displaceably in a groove 32 which is provided for on plate 12 and which runs at right angles to the direction of the slide rail 30 and can be clamped in position. To clamp each slide 28 in position, provision is made of a screw 33 with square head 34 and a clamping nut 35 whose shaft slides in a slot 36 running in the direction of groove 32 and whose head 34 slides in a groove 37. The mask-parts are attached to the respective cross slide 28 by means of a supporting pin 38 for which on plate 12 a slot 39 is provided running in the direction of groove 32. The register marks 5 are being illuminated by an incandescent lamp 40 each. The latter lamps are to be imagined to be connected to a mutual source of energy by means of a rheostat. As indicated on the left half of Fig. 3 the adjustment of the mask-parts can be effected according to a graduation 41 on plate 12 by means of a pointer 42 (Fig. 2) provided for on the supporting body 27.

Fig. 5 shows a diagram of a further constructional example designed for producing a virtual image of register mark 5. The register mark is provided for on one of the lateral surfaces of a prism 43 and is being illuminated by the light-source 40 through the reflecting surface 44. The register mark lying between the lens and its focal plane it is being presented by means of a collective lens 45, to the objective 7 of the reproduction apparatus as lying in the object-plane.

I claim:

1. A reproduction apparatus for making color separations according to a colored specimen comprising an object carrier, means for attaching a colored specimen on said object carrier, a light source being adapted to illuminate said specimen, an optical system adapted to image said specimen on a photo-sensitive layer, a plurality of register marks, each of said register marks being disposed displaceably on said object-carrier parallel to the plane containing said specimen, and optical means adapted to present said register marks to said optical system as lying in the plane of said specimen near to the margin of the latter.

2. A reproduction apparatus for making color separations according to a colored specimen comprising an object carrier, means for attaching a colored specimen on said object carrier, a light source being adapted to illuminate said specimen, an optical system adapted to image said specimen on a photo-sensitive layer, a plurality of register marks, each of said register marks being disposed displaceably on said object-carrier parallel to the plane containing said specimen, optical means adapted to present said register marks to said optical system as lying in the plane of said specimen near to the margin of the latter, and illuminating means regulatable in brightness and adapted to illuminate said register marks.

3. A reproduction apparatus for making color separations according to a colored specimen comprising an object carrier, means for attaching a colored specimen on said object carrier, a light source being adapted to illuminate said specimen, an optical system adapted to image said specimen on a photo-sensitive layer, a plurality of register marks, each of said register marks being disposed displaceably on said object-carrier parallel to the plane containing said specimen, optical means adapted to present said register marks to said optical system as lying in the plane of said specimen near to the margin of the latter, and a plurality of cross slides being placed on said object carrier, each of said cross slides carrying one of said register marks and one of said optical means.

4. A reproduction apparatus for making color separations according to a colored specimen comprising an object carrier, means for attaching a colored specimen on said object carrier, a light source being adapted to illuminate said specimen, an optical system adapted to image said specimen on a photo-sensitive layer, a plurality of register marks, each of said register marks being disposed displaceably on said object-carrier parallel to the plane containing said specimen, optical means adapted to present said register marks to said optical system as lying in the plane of said specimen near to the margin of the latter, and a plurality of diaphragms serving to bound the picture, each of said diaphragms being adjustably mounted on said object-carrier.

5. A reproduction apparatus for making color separations according to a colored specimen comprising an object-carrier, means for attaching a colored specimen on said object carrier, a light source being adapted to illuminate said specimen, an optical system adapted to image said specimen on a photo-sensitive layer, a plurality of register marks, each of said register marks being disposed displaceably on said object-carrier parallel to the plane containing said specimen, optical means adapted to present said register marks to said optical system as lying in the plane of said specimen near to the margin of the latter, and a plurality of diaphragms serving to bound the picture, each of said diaphragms being adjustably mounted on said object-carrier and connected with one of said register marks.

CARL HERRMANN.
